UNITED STATES PATENT OFFICE

PINK T. BYNUM, OF CALLIHAM, TEXAS

PIN AND BUSHING REMOVING TOOL

Application filed April 16, 1931. Serial No. 530,675.

This invention relates to a pin and bushing removing tool and especially to a device of this character which is particularly intended for use in removing king pins and their bushings from the front axles of automobiles but it is understood, of course, that a tool in accordance with this invention may be used for any purpose and in any manner for which the same may be found adapted and desirable.

An important object of the invention is to provide, in a manner as hereinafter set forth, a tool of the character described embodying a novel construction and arrangement of parts whereby said tool may be expeditiously adjusted for use on the different axles which may be found in various makes of automobiles.

Other objects of the invention are to provide a pin and bushing removing tool of the character set forth which will be simple in construction, strong, durable, efficient and reliable in use and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view principally in side elevation and partly broken away in vertical longitudinal section showing a tool in accordance with this invention mounted in operative position on an angle.

Figure 2 is a view in vertical section through the axle taken substantially on the line 2—2 of Figure 1 looking in the direction indicated by the arrows and showing the tool in end elevation.

Referring now in detail to the drawings, it will be seen that the reference numeral 1 designates a beam having a ratchet bar 2 disposed for vertical sliding movement through one end portion thereof, said ratchet bar having a yoke 3 on its upper end for engagement with the axle 4. A keeper 5 is slidably mounted on the beam 1 and is yieldingly

urged toward the ratchet bar 2 by a suitable spring for securing said ratchet bar in adjusted position on the beam 1.

The other end of the beam 1 is suspended from the axle 4 through the medium of a hanger which is designated generally by the reference numeral 6 and which comprises a pair of spaced, parallel bars 7 having removable pins 8 and 9 extending between the upper and lower end portions thereof respectively. Rollers 11 having tapered or conical inner portions are journaled on the pin 8 and rollers 11' are journaled on the lower pin 9, the rollers on the upper pin being adapted for travel over the axle 4 and the rollers on the pin 9 having rolling contact with the lower side of the beam 1. The shape of the rollers 11 is such that said rollers conform substantially to the upper side of the axle. The bars 7 are slidable on the end portions of the pins 8 and 9 and are adapted to be clamped against the sides of the beam 1 and the axle 4 by a clamping screw 10 extending through intermediate portions of said bars. A jack screw 12 is threaded for vertical adjustment through said other end portion of the beam 1 and has formed on its lower end a polygonal head 13 for engagement by a suitable tool, such as a wrench, for operating the jack screw. The other end of the jack screw 12 tapers to a point, as at 14 for engagement with the lower end of the king bolt 15 which mounts the knuckle 16 for swinging movement on the axle 4, said knuckle 16 having the usual spindle 17 extending therefrom. Said other end portion of the jack screw 12 is also stepped in a manner to provide shoulders for abutting engagement with the bushings between the king bolt 15 and the eyes of the knuckle 16 for removing said bushings.

Obviously, the tool may be expeditiously adjusted as desired. When the jack screw 12 is threaded upwardly against the king bolt or bushings, the ratchet bar 2 prevents the beam 1 from fulcruming on the hanger 6. The keeper 5 may be retracted by any suitable means, such as a pin projecting laterally therefrom and operable in a longitudinal slot (not shown) provided at one side of the beam.

By clamping the bars 7 against the beam 100

1 and the axle 4, said beam is maintained directly beneath the axle and is prevented from canting, thus maintaining the jack screw in alignment with the pin or bushing.

5 It is believed that the many advantages of a pin and bushing removing tool constructed in accordance with this invention will be readily understood, and although the preferred embodiment of the invention is as illustrated and described, it is to be understood that changes in details of construction may be had in the combination and arrangement of parts which will fall within the scope of the invention as claimed.

10 15 What is claims is:—

1. A pin and bushing removing tool comprising a supporting hanger including a pair of spaced, parallel bars for disposition on opposite sides of a support, removable pins 20 extending between the end portions of the bars, a fixed pin extending between intermediate portions of the bars, substantially conical pairs of rollers journaled on the first named pins, between the bars, the rollers constituting each pair having their small ends disposed adjacent each other, the rollers on the uppermost pin being adapted for rolling contact with the support, a beam slidable between the bars on the lowermost rollers, a 25 jack screw threaded through one end portion of the beam for engagement with the pins and bushings, and means adjustably mounted on the other end portion of the beam and engageable with the support in a manner 30 to retain the beam against swinging movement on the lower rollers when the jack screw is actuated.

2. A pin and bushing removing tool comprising a beam, means for mounting said beam 40 on a support, said means including a pair of spaced, parallel bars extending on opposite sides of the support and the beam, pins extending between the bars above and below the support and the beam respectively, said bars 45 being slidable on the pins, rollers journaled on the pins and engageable with the upper side of the support and the lower side of the beam, a clamping screw extending through intermediate portions of the bars for clamping 50 said bars against the support and the beam, a jack screw threaded through one end portion of the beam for operative engagement with the pin or bushing to be removed, and means on the other end portion of the 55 beam engageable with the support in a manner to prevent swinging movement of the beam toward said support.

3. A pin and bushing removing tool comprising a hanger including a pair of bars, a 60 roller journaled transversely between the bars for rolling contact with a support, another roller journaled transversely between the bars in spaced relation to the first named roller, a beam operable between the bars on the second named roller, a jack screw operatively mount-

ed on one end portion of the beam, and means on the other end portion of the beam engageable with the support for retaining the beam against swinging movement when the jack screw is actuated.

70 In testimony whereof I affix my signature.
